FIG. 10

UNITED STATES PATENT OFFICE.

GEORGE B. ADAMS, OF IRVINGTON, NEW JERSEY.

BADGE.

SPECIFICATION forming part of Letters Patent No. 650,962, dated June 5, 1900.

Application filed January 13, 1900. Serial No. 1,275. (No model.)

To all whom it may concern:

Be it known that I, GEORGE B. ADAMS, a citizen of the United States, residing at Irvington, in the county of Essex and State of New Jersey, have invented certain new and useful Improvements in Badges; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in that class of badges comprising a main body portion for the displaying thereon of an inscription, insignia, or other desirable design, provided at the back with a pin for the attachment of the badge upon a garment. The invention therefore has for its principal objects to provide an improved badge and a novel construction of top bar or headpiece, principally made in the manner to be herein-after more fully set forth.

The invention also has for a further object to provide a novel construction of pin for the attachment of the same to a badge and, further, the novel arrangement and construction of various parts of said pin and the top bar or headpiece of the badge, whereby a simple and cheap as well as an ornamentally-constructed device is the result, the parts of which can be easily and quickly assembled to provide a neat badge to be worn on the lapel or any other part of a garment.

The invention therefore consists in the improved badge and novel construction of head-bar or top piece and pin therefor, all to be hereinafter set forth; and, furthermore, my invention consists in such novel arrangements and combinations of parts, as well as in the details of the construction thereof, all of which will be fully described in the accompanying specification and finally embodied in the clauses of the claim.

The invention is clearly illustrated in the accompanying sheet of drawings, in which—

Figures 1 and 2 are a face and back view, respectively, of a ribbon badge and one form of top bar or headpiece made according to the principles of my invention. Fig. 3 is a horizontal section of the top bar or headpiece

on an enlarged scale, said section being taken on line 3 3 in Fig. 2; and Fig. 4 is a vertical cross-section of the top bar or headpiece, said section being taken on line 4 4 in Fig. 3 looking in the direction of arrow *x*. Fig. 5 is a perspective view of the preferred form of pin to be used with said top bar or headpiece. Figs. 6 and 7 are a face and back view, respectively, of a modified form of top bar or headpiece, but still made according to the principles of my invention. Fig. 8 is a horizontal section taken on line 8 8 in Fig. 7 with the pin omitted, and Fig. 9 is a vertical cross-section taken on line 9 9 in said Fig. 7. Fig. 10 is a horizontal section of a top bar or headpiece made according to my invention, illustrating its use with an ornamental frame.

Similar letters of reference are employed in all of the said above-described views to indicate corresponding parts.

In said drawings, *A* indicates the complete top bar or headpiece for a ribbon *b*. In Figs. 1 to 4, inclusive, the top bar or headpiece is represented as being struck up from a blank *a*, of sheet metal or any other suitable material, said blank being suitably ornamented on its face and having an ornamental configuration in outline of any desirable shape. The central portion of the main surface of said blank *a* is preferably provided with a suitable opening *a'*, through which may be seen the reading-surface *a³* of another blank *a²*, of cardboard, celluloid, or other material. Upon the face *a³* can be printed or otherwise arranged a word or words or an insignia, emblem, picture, or the like. At or near the opposite ends of said blank *a*, which forms the top bar or headpiece, as above set forth, I have arranged a pair of backwardly-projecting lugs *a⁴*, each lug having a receiving portion or loop *a⁵* for the respective curved or bent ends *c²* and *c³* of a pin-bar *c*, the said receiving portions *a⁵* in the construction set forth in said Figs. 1 to 4, inclusive, being sufficiently closed down to secure said blank *a²* against the back of the top bar or headpiece and to operatively hold and retain the pin-bar *c* in place on the back of said top bar. The said pin-bar *c* consists, essentially, of a main body portion *c'*, on which may be arranged the folded-over portion *b'* of the ribbon *b*, as shown, the said body portion *c'*,

as above stated, having at one end a curved portion c^2 and at the opposite end a curved portion c^3 . Extending in an upwardly and inwardly inclined direction toward the middle 5 of the said main body portion c' is an arm c^4 , having at its free end a curved portion c^5 , bent at an angle to said arm c^4 , substantially in the manner illustrated, to form a pin-guard. The opposite end portion c^3 of said body portion 10 c' has an upwardly and inwardly extending arm c^6 , which is connected with an arm c^7 , preferably by a curved portion c^8 , all arranged so that the arms c^4 and c^6 and the main portion c' , when the portions c^2 and c^3 of the body portion 15 c' have been sprung under the receiving portions or loops a^5 of the lugs a^4 , will rest directly against the back of the top bar or head-piece A, with an arm c^7 extending in a direction away from the back of the said top bar 20 or headpiece A and having a spring action, whereby the pin can be readily forced under the looped pin-guard c^5 , substantially as illustrated in Figs. 2 and 3 of the drawings. The free end of said pin-bar c^7 is preferably provided with a pin-point c^9 for forcing the pin-bar c^7 readily through the fabric when the badge is to be attached to a garment or on a 25 display-card.

From the above description it will be seen 30 that the construction of the various parts is very simple and can be readily assembled, the pin being held in place without the use of solder, which is objectionable during the process of manufacture while putting the finished parts together on account of the 35 heat required, and which is especially objectionable when the parts are covered with celluloid or similar material, as will be presently set forth.

40 In lieu of the construction of top bar or headpiece described in the above the said top bar or headpiece may be made, as clearly indicated in Figs. 6 to 10, inclusive, to adapt it more especially in use with a celluloid or other suitable covering d , which is 45 usually transparent, so as to permit of the placing therebeneath of a plate or blank e , which may be provided with an inscription, emblem, or design, as will be hereinafter 50 more fully set forth. In said Figs. 6, 7, 8, and 9, a^6 indicates a suitably-shaped shell or plate of metal, which is preferably formed with an inwardly-projecting marginal rim or bead a^7 , thereby forming a chambered portion a^8 in the back of said shell or plate. 55 Upon this shell I prefer to place the plate or blank e , usually provided with an inscription, design, or the like, as stated, and upon this I place a covering d , of celluloid or any other 60 similar material. It must be understood, however, that the plate or blank e may be dispensed with and that an inscription, emblem, design, or picture may be produced directly 65 upon such celluloid or other similar covering, if desired. In the construction represented the marginal rim e' of said plate or blank e and the marginal edge d' of said covering d

are both arranged over and underneath the said marginal rim or bead a^7 of the shell or plate a^6 , where said edges are held fast and 70 pulled taut by the surrounding and inwardly-extending marginal edge a^{10} of a back-plate a^9 , as clearly illustrated; but of course it will be clearly evident that the said plates a^6 and a^9 may be connected and secured together 75 in any other well-known manner. In this construction of back-plate a^9 the latter is provided at or near its ends with holding loops or lugs a^{11} , which loops or lugs are forced up from said back-plate and extend back therefrom to provide a pair of receiving portions 80 for the reception of the curved end portions c^2 and c^3 of the main body portion c' of the pin-bar c . When thus made the inner surfaces of 85 said loops or lugs a^{11} are curved, thereby practically forming chambers a^{12} with the side walls a^{13} , which, however, are cut away, as at a^{14} , for the entrance of said portions of the pin-bar c into said chambers by springing the same beneath said lugs or loops a^{11} , and then 90 by the spring-pressure of the parts of said spring against the side walls a^{13} being firmly retained in place, as will be clearly understood. In some cases, if found desirable, the back-plate a^9 may be provided with suitable loops 95 or lugs, as a^{15} , whereby said shell or plate a^6 and the back-plate a^9 may be arranged in a box-like frame f , having a marginal projecting edge f' fitting around said parts and a back f^2 provided with slots or openings f^3 , 100 through which the said lugs or loops a^{15} are passed, so as to extend beyond the back of said frame, for securing the pin c in position in the manner hereinabove described, as will be clearly evident from an inspection of Fig. 10. 105

Instead of securing the upper end of the ribbon b directly upon the main body portion c' of the pin c , as indicated in Figs. 2, 3, and 4, the upper end of the ribbon can be arranged and clamped between the marginal edges of 110 the plates a^6 and a^9 , as clearly indicated in Figs. 7 and 9.

From the above description it will be seen 115 that I have devised a neat and simply-constructed top-bar and pin attachment for badges the parts of which can be quickly assembled and with a great reduction in the cost of manufacture.

It will be obvious that changes may be made 120 in the various arrangements and combinations of parts, as well as in the details of the construction thereof, without departing from the scope of this invention. Hence I do not limit my invention to the exact arrangements and combinations of the parts as herein described and illustrated, nor do I confine myself to the details of the construction of such parts.

Having thus described my invention, what 130 I claim is—

1. A badge-bar comprising a body portion having inwardly-projecting lugs or loops at or near the ends thereof, said lugs or loops having openings at their inner ends and pro-

vided with side walls, and a pin-bar provided with holding portions arranged and retained in said lugs or loops in contact with the side walls thereof, substantially as and for the 5 purposes set forth.

2. A badge-bar comprising a body portion having holding lugs or loops, and a pin-bar having portions thereof connected with said lugs or loops, said pin-bar consisting, essentially, of a main body portion, a curved end portion at each end of said main body portion, an inwardly-extending arm portion connected with each of said curved end portions and arranged in the same plane with the main 10 body portion, or approximately so, and extending toward each other in a direction parallel with the longitudinal axis of said body portion, and a pin-point on one of said inwardly-extending arm portions, substantially as and for the purposes set forth.

3. A badge-bar comprising a body portion having holding lugs or loops, and a pin-bar having portions thereof connected with said lugs or loops, said pin-bar consisting, essentially, of a main body portion, a curved end portion at each end of said main body portion, an inwardly-extending arm portion connected with each of said curved end portions and arranged in the same plane with the main 15 body portion, or approximately so, and a pin-point on one of said inwardly-extending arm portions, and a ribbon, having a looped or turned-over edge arranged over the main body portion of said pin, substantially as and for the purposes set forth.

4. A badge-bar comprising a body portion having inwardly-projecting lugs or loops at or near the ends thereof, a pin-bar consisting, essentially, of a main body portion and 20 curved end portions, said curved parts being arranged in and retained beneath said lugs or loops, arm portions connected with said curved parts extending inward toward each other in the vertical plane of the main body portion, or approximately so, a pin-guard on 25 one of said arm portions and a pin on the other of said arm portions, arranged to be forced beneath said pin-guard, substantially as and for the purposes set forth.

5. A badge-bar comprising a body portion having inwardly-projecting lugs or loops at or near the ends thereof, a pin-bar consisting, essentially, of a main body portion and curved end portions, said curved parts being 30 arranged in and retained beneath said lugs or loops, arm portions connected with said curved parts extending inward toward each other in the vertical plane of the main body portion, or approximately so, a pin-guard on 35 one of said arm portions and a pin on the other of said arm portions, arranged to be forced beneath said pin-guard, and a ribbon, having a looped or turned-over upper edge arranged over the main body portion of said 40 pin-bar, substantially as and for the purposes set forth.

6. A badge-bar comprising a body portion

having inwardly-projecting lugs or loops at or near the ends thereof, a pin-bar consisting, essentially, of a main body portion and 45 curved end portions, said curved parts being arranged in and retained beneath said lugs or loops, arm portions connected with said curved parts extending inward toward each other in the vertical plane of the main body portion, or approximately so, a pin-guard on 50 one of said arm portions at a right angle thereto, or approximately so, and a pin connected with the other of said arm portions having a backwardly-extending part to throw 55 said pin out of said vertical plane of the main body portion of the pin-bar, and its pin-point in line with the pin-guard for its reception therebeneath, substantially as and for the 60 purposes set forth.

7. A badge comprising a shell or plate having a curved marginal rim or bead, a back-plate having an inwardly-curved marginal rim or bead, arranged beneath the marginal rim or bead of said shell or plate, lugs or 65 loops on said back-plate, having side walls, and a pin-bar *c*, consisting, essentially, of a straight body portion *c'*, curved end portions connected therewith arranged beneath said lugs or loops in spring contact with the side 70 walls thereof, inwardly-extending arm portions connected with said curved parts, a pin-guard on one of said arm portions, and a pin connected with the other of said arm portions, and extending backwardly therefrom 75 at the point of connection between said arm portion and the said pin to form a spring-bearing for said pin, and permit the insertion of its free end beneath said pin-guard, substantially as and for the purposes set forth.

8. The herein-described pin-bar *c*, consisting, essentially, of a main body portion *c'*, provided with curved end portions, an arm *c⁴* connected with one of said curved portions, and an arm *c⁶* connected with the other of said curved portions, said arms *c⁴* and *c⁶* and the main body portion *c'* all being in the same vertical plane, or approximately so, a pin-guard at the free end of said arm *c⁴* extending at a right angle therefrom, or approximately so, an arm *c⁷* connected with and forming a part of said arm *c⁶* extending in a direction away from the same in a plane at right angles to the vertical plane through said body portion *c'* and said arm portions *c⁴* 110 and *c⁶*, and said arm *c⁷* having a pin-point at its free end, substantially as and for the purposes set forth.

9. A badge-bar comprising a body portion, consisting of a shell or plate having a marginal rim or bead, and a back-plate having a marginal rim or bead, arranged beneath the marginal rim or bead of said shell or plate, inwardly-projecting side and end portions on said back-plate forming receiving-chambers, 125 said side portions extending inwardly in a direction parallel with the longitudinal central axis of said badge-bar, or approximately so, and a pin-bar, consisting, essentially, of

a main body portion, and curved end portions arranged in said receiving-chambers, arm portions connected with said curved end portions extending inwardly toward each other 5 in the vertical plane of the main body portion, approximately so, and a pin-point connected with one of said arm portions, substantially as and for the purposes set forth.

10. A badge-bar comprising a body portion having holding lugs or loops and a pin-bar having portions thereof connected with said lugs or loops, said pin-bar consisting, essentially, of a main body portion and curved end portions, arm portions connected with

15 said curved parts extending inward toward each other in the same plane of the main body portion, or approximately so, a pin-guard on one of said arm portions and a pin-point on the other of said arm portions arranged to be forced beneath said pin-guard, substantially 20 as and for the purposes set forth.

In testimony that I claim the invention set forth above I have hereunto set my hand this 11th day of January, 1900.

GEORGE B. ADAMS.
